UNITED STATES PATENT OFFICE.

PERCY METZGER, OF WASHINGTON, DISTRICT OF COLUMBIA.

CANISTER.

SPECIFICATION forming part of Letters Patent No. 363,664, dated May 24, 1887.

Application filed November 20, 1886. Serial No. 219,467. (No model.)

To all whom it may concern:

Be it known that I, PERCY METZGER, a citizen of the United States, residing at Washington, in the District of Columbia, have invented 5 certain new and useful Improvements in Canisters; and I do hereby declare the following to be a full, clear, and exact description of the invention, such as will enable others skilled in the art to which it appertains to make and 10 use the same.

My invention is a canister for containing and displaying teas, coffees, spices, &c.; and it consists in the parts which will be herein-after described, and pointed out in the claims. 15 In the accompanying drawings, Figure 1 represents a perspective view of my invention. Fig. 2 is a central vertical section. Fig. 3 is a perspective view of the detachable top. Fig. 4 is a perspective view of a canister without 20 the detachable top. Fig. 5 is a central vertical section of the construction shown in Fig. 4. Fig. 6 is a vertical sectional detail of the top of a canister wherein only one top door is employed, and Fig. 7 is a detail perspective 25 showing the means for securing the door of the pocket.

The objects of my invention are to produce a canister which may be quickly filled with tea, coffee, or spice, &c., and the same easily 30 removed therefrom at pleasure; also, a canister which will at all times display a certain quantity of an article in a top receptacle irrespective of the quantity of the article in the main body of the canister, the contents of the display pocket or receptacle being visible through 35 a glass door, all of which will be more fully hereinafter specified.

Referring to the drawings by letters, A represents the main body of the canister, and B 40 the removable top thereof.

C represents a frusto-conical shelf having its outer edges secured to the inner lower sides of the canister.

D are two bottom side doors—one on each 45 side of the canister. These doors are immediately under the shelf C. Said shelf acts as a deflector for the contents of the canister—that is to say, the shelf causes the contents of the canister to flow centrally on the floor, and 50 thereby prevents said contents from clogging around the inner sides of the doors.

When the canister is constructed in cylindrical form, as shown in the drawings, the doors D are curved, so as to conform to the circular configuration of the canister. The 55 doors slide circumferentially in curved guide-flanges.

The canister is provided with an opening immediately under each door, whereby, when the doors are open, access may be had to the 60 bottom of the canister for the purpose of removing any desired quantity of the contents. A scoop may be advantageously employed in removing the contents through these side openings. Each door is independent of the other, 65 whereby access may be had to the canister from either side.

B represents the removable top in which is located a side pocket for the reception and display of a sample which shall correspond with 70 the contents of the main portion of the canister. This pocket consists of a vertical wall, B', and a horizontal semicircular floor, B''. The outer sides of the pocket are formed by the outer walls of the canister B'. The side of the 75 canister in which the pocket is located is cut away from a point near the center of the top outward and downward to a point on the side equal to about one half the depth of the vertical wall B'. A similar bevel cut is made in 80 the opposite top and side of the canister.

F represents a door hinged to one side of a strip, G, on the top of the canister. This door is provided with a glass, G', suitably secured thereto, through which the contents of the 85 pocket may be seen. A small opening, H, is made in one side of the top strip, G, which communicates with the display-pocket.

H' is a small door pivoted to the upper side of strip G, by means of which said opening 90 may be closed. This opening is adapted to receive the end of a funnel, whereby the pocket may be completely filled. It is desirable to completely fill the pocket, so that the display may be more conspicuous. In order that the 95 door F may not be forced open by the contents of the pocket when it is filled to the top, I provide the inner side of said door near its outer edge with a ball-catch, f, which engages a small projection, f', on the inner top side of the 100 pocket. By this means the door may be firmly closed. F' is a knob on the outer top side of

the door F, whereby said door may be opened or closed. The ball-catch f is spring-actuated by means of its shank f'. The spring is of sufficient strength to cause the ball to pass 5 around to the under side of the projection f' when the door is closed, so as to retain the door and prevent the same from being opened by the outward pressure of the contents of the pocket when the same is filled; but the door 10 may, however, be easily opened by hand.

The letter N represents an opening in the lower side of the vertical wall. N' is a sliding door for closing said opening. This door is provided with front and rear knobs, whereby 15 the door may be opened from the pocket side or from the opposite or rear side of the wall. The door is mounted in and slides on flanged ways. (Notshown.) The object of said opening and door is to permit the discharge of the 20 contents of the pocket into the main body of the canister.

I represents a door having its inner end hinged to one side of the top strip, G. This door is adapted to close the bevel-opening I'. Said opening communicates with the interior 25 of the main body of the canister. There are two ways of filling the canister. One is through the door I and opening I', and the other is by removing the top. Access may also 30 be had through the opening I' for the purpose of removing desired quantities of the contents from the main body of the canister.

Near the top inner part of the main body of the canister is a circular band, J. This band 35 is rigidly united to the canister, its object being to impart strength. The under side of the removable top is provided with a circumferential flange, K, which is of less diameter than the diameter of said top, so that the flange

will fit snugly within the top. Said flange is 40 provided with a right-angled recess, K', formed in its edge. A pin, K'', is fixed to the inner side of the canister near the top thereof. The removable top is secured to the main 45 body of the canister by means of said pin and recess. There may be one or more of these pins and recesses. In uniting the top with the body the vertical portion of the recess is set over the pin. The top is then lowered and then slightly 50 turned, whereby said top and bottom are firmly united.

L represents the feet upon which the canister is mounted, and M indicates the handles by which the device may be manipulated.

Having thus described my invention, I claim 55 as new and desire to secure by Letters Patent—

1. A canister-body provided with a removable-top, said top being provided on one side with a pocket and provided on the other side with an opening communicating with the main 60 body of the canister, said top being provided with a flange whereby it may be engaged with the canister, substantially as described.

2. A canister provided with a removable top, said top being provided with a pocket, 65 said pocket being provided with an opening communicating with the main body of the canister and a door for closing said opening, said top being also provided with an opening 70 communicating with the main body of the canister, also provided with a flange for engaging the canister, substantially as described.

In testimony whereof I affix my signature in presence of two witnesses.

PERCY METZGER.
